UNITED STATES PATENT OFFICE.

CYRUS J. WEBER, OF STEELTON, PENNSYLVANIA, ASSIGNOR OF ONE-HALF
TO THOMAS J. RAFTERY, OF CUMBERLAND, MARYLAND.

COMBINED LEVEL AND GRADE-FINDER.

SPECIFICATION forming part of Letters Patent No. 739,242, dated September 15, 1903.

Application filed December 18, 1902. Serial No. 135,767. (No model.)

To all whom it may concern:

Be it known that I, CYRUS J. WEBER, a citizen of the United States, residing at Steelton, in the county of Dauphin and State of Pennsylvania, have invented a new and useful Combined Level and Grade-Finder, of which the following is a specification.

This invention relates to devices employed for leveling purposes by mechanics and engineers and which may also be employed for ascertaining the grades or inclination of roads, bridges, and other structures, and has for its object the production of a simple and inexpensive instrument which may be employed for all the various purposes of an ordinary mechanic's level, combined with an implement whereby much of the work heretofore requiring the use of expensive and cumbersome engineering instruments may be accomplished by persons who are not skilled engineers.

The invention consists in certain novel features of construction, as hereinafter shown and described, and specified in the claims.

In the drawings illustrative of the invention, in which corresponding parts are denoted by like designating characters, Figure 1 is a longitudinal section elevation. Fig. 2 is an end elevation. Fig. 3 is a transverse section on the line 3 3 of Fig. 1.

The body or stock indicated at 10 is of the structure employed in ordinary spirit-levels, with parallel sides and forming a "straight-edge" and provided with the usual spirit or mercury leveling bulb 11, located in a recess therein.

Formed partially through the stock 10 is a longitudinal aperture 14, preferably located near the lower edge, or the edge farthest from the spirit or mercury bulb 11, and intersected by a lateral aperture 14, extending partially through the stock from its upper edge, as shown. The lateral aperture 14 will preferably be formed diverging outwardly from its intersection with the aperture 13, so that the "eyepiece" 15 at the outer end will be larger than the inner end. At the intersection of the aperture an inclined mirror 16 will be located and so placed that the beams of light passing through the aperture 13 will be re-

flected centrally through the lateral aperture 14, as indicated by dotted line in Fig. 1.

Within the aperture 13 are located transverse hair-lines, (indicated at 17 18,) one preferably at the outer end of the aperture and the other at an intermediate point between the mirror and the outer end of the aperture. The hair-lines will be arranged in substantially the same manner and employed for the same purpose as the hair-lines of engineers' or surveyors' instruments, and it will be obvious that they must be placed in such exact relations to the side edges of the stock 10 as to denote the exact position of objects with which they are alined. By this simple arrangement it will be obvious that if the stock 10 be adjusted until the bubble in the bulb 11 be exactly "centered" therein whatever object appears in alinement with the hair-line 17 18 when reflected through the eyepiece 15 will be exactly level with the center of the aperture 13. The operator can thus very readily ascertain the exact relative position of widely-separated objects with as much exactness and certainty as with the more expensive and cumbersome engineering instruments, and being so simple and convenient in structure it may be readily transported and employed in many places where it would be very difficult to use the ordinary surveyor's instrument. The instrument will not weigh more than the ordinary carpenter's or mechanic's level and may be as readily transported and stored.

To enable the instrument to be employed for ascertaining grades or inclinations, a graduated dial 19 will be arranged with a recess 20 in the stock 10 and with a pointer 22, pivoted at 23 and adapted to move over the graduations, it being understood that the relative locations of the pivot 23 and central graduation of the dial will be so disposed that the operative end of the pointer will be opposite the central graduation when the stock 10 is level. Transversely disposed in the aperture 20 is a shaft 24, and suspended from this shaft is a swinging weight 25. Connecting the free end of the weight 25 and the pointer 22 is a rod 26, so that the swinging movement of the weight will be imparted to the pointer. 100

By this simple arrangement it will be obvious that any change of position of the stock 10 will not be imparted to the weight 25, which will be maintained by gravity at all times in 5 a vertical position, and by means of the connecting-rod 26 and dial 19 the degree of change of position will be denoted upon the dial by the pointer.

The dial 19 will be graduated upon both 10 faces and located intermediately of the recess 20, so as to be visible from both sides of the stock 10, and the point 22 will be divided with a portion upon each side of the dial, so that no matter from which side of the stock the 15 dial is viewed it may be "read." This is a very convenient arrangement and adds materially to the usefulness of the instrument.

One of the graduated dials and its connected swinging weight will be arranged 20 transversely of the stock to denote the degree of angularity when the instrument is used perpendicularly; but the mode of action and results produced are substantially the same as when the stock is employed in a horizontal 25 position.

The instrument may be of any desired size and material and may be modified in minor particulars without departing from the principle of the invention or sacrificing any of its 30 advantages.

Having thus described my invention, what I claim is—

1. In a combined level and grade-finder, a stock or body member, an aperture longitudinally disposed within said stock, a lateral aperture in said stock intersecting said longitudinal aperture, an inclined mirror disposed at the juncture of the two apertures and adapted to reflect the beams of light passing through said longitudinal aperture centrally through said lateral aperture, and pairs of intersecting hair-lines spaced apart within said longitudinal aperture, substantially as described.

2. In a combined level and grade-finder, a stock or body member, an aperture longitudinally disposed within said stock, a lateral aperture in said stock intersecting said longitudinal aperture, and converging toward its 50 inner end, an inclined mirror disposed at the juncture of the two apertures and adapted to reflect the beams of light passing through said longitudinal aperture centrally through said lateral aperture, and pairs of intersecting hair-lines spaced apart within said longitudinal aperture, substantially as described.

3. In a combined level and grade-finder, a stock or body member, a spirit-bubble connected to said stock, an aperture longitudinally disposed within said stock, a lateral aperture in said stock intersecting said longitudinal aperture, an inclined mirror disposed at the juncture of the two apertures and adapted to reflect the beams of light passing 65 through said longitudinal aperture centrally through said lateral aperture, and pairs of intersecting hair-lines spaced apart within said

longitudinal aperture, substantially as described.

4. In a combined level and grade-finder, a stock or body member provided with a recess, an aperture longitudinally disposed within said stock, a lateral aperture in said stock intersecting said longitudinal aperture, an inclined mirror disposed at the juncture of the two apertures and adapted to reflect the beams of light passing through said longitudinal aperture centrally through said lateral aperture, a graduated dial, a pointer movable over said dial, and a swinging weight 80 operatively connected to said dial, said dial, pointer and weight being located within the stock-recess, substantially as described.

5. In a combined level and grade-finder, a stock or body member having parallel sides 85 and being provided with a recess, an aperture longitudinally disposed within said stock, a lateral aperture in said stock intersecting said longitudinal aperture disposed between said parallel sides, an inclined mirror disposed at the juncture of the two apertures and adapted to reflect the beams of light passing through said longitudinal aperture centrally through said lateral aperture, a graduated dial, a pointer movable over said dial, a 95 swinging weight, and means between the weight and pointer whereby the movement of the weight will be imparted to the pointer, said dial, pointer and weight being located within the stock-recess, substantially as described.

6. In a combined level and grade-finder, a stock or body member, an aperture longitudinally disposed within said stock, a lateral aperture in said stock intersecting said longitudinal aperture, an inclined mirror disposed at the juncture of the two apertures and adapted to reflect the beams of light passing through said longitudinal aperture centrally through said lateral aperture, a graduated dial, a 110 pointer movable over said dial, a swinging weight, and a rod connecting said weight and pointer, whereby the movement of the weight will be imparted to the pointer, substantially as described.

7. In a combined level and grade-finder, a stock or body member, an aperture longitudinally disposed within said stock, a lateral aperture in said stock intersecting said longitudinal aperture, an inclined mirror disposed at the juncture of the two apertures and adapted to reflect the beams of light passing through said longitudinal aperture centrally through said lateral aperture, an aperture transversely disposed through said stock, a 125 dial graduated upon its opposite surfaces and disposed within said transverse aperture and visible from both sides of the stock, a divided pointer disposed to move over both sides of said dial, a swinging weight, and means 130 whereby the movement of said weight is imparted to the pointer, substantially as described.

8. In a combined level and grade-finder, a

stock or body member provided with a plurality of recesses, an aperture longitudinally disposed within said stock, a lateral aperture in said stock intersecting said longitudinal aperture, an inclined mirror disposed at the juncture of the two apertures and adapted to reflect the beams of light passing through said longitudinal aperture centrally through said lateral aperture, a graduated dial, a pointer 5 movable over said dial, and a swinging weight operatively connected to said dial, said dial, pointer and weight being located within one of the stock-recesses, and a spirit-bubble located within another stock-recess, substantially as described.

9. In a combined level and grade-finder, a supporting stock or body member, a graduated dial, a pointer movable over said dial, a transverse shaft, a weight swinging upon said 20 shaft, and a rod connecting the free end of said pointer, whereby the movement of said weight will be imparted to said pointer, substantially as described.

10. In a combined level and grade-finder, a supporting stock or body member provided 25

with a plurality of recesses, a spirit-bubble located within one of said stock-recesses, a graduated dial, a pointer movable over said dial, a swinging weight, and connecting means between said weight and pointer, whereby the movement of the weight will be imparted to the pointer, said dial, pointer and weight being located within another stock-recess, substantially as described.

11. In a combined level and grade-finder, a supporting stock or body member, a spirit-bubble connected to the stock, a graduated dial, a pointer movable over said dial, a transverse shaft, a weight swinging upon said shaft, and a rod connecting the free end of 30 said weight with said pointer, substantially as described.

In testimony that I claim the foregoing as my own I have hereto affixed my signature in the presence of two witnesses.

CYRUS J. WEBER.
